UNITED STATES PATENT OFFICE.

JAMES W. PATTERSON, OF NEW YORK, N. Y., ASSIGNOR TO AUTOSALES GUM AND CHOCOLATE COMPANY, OF NEW YORK, N. Y., A CORPORATION OF NEW YORK.

COIN-CONTROLLED LOCK.

1,146,018.

Specification of Letters Patent. Patented July 13, 1915.

Application filed July 2, 1907. Serial No. 381,836.

To all whom it may concern:

Be it known that I, JAMES W. PATTERSON, of the city of New York, county of Kings, and State of New York, have invented an

5 Improvement in Coin-Controlled Locks, of which the following is a specification.

My invention has reference to coin controlled locks and consists of certain improvements which are fully set forth in the 10 following specification and shown in the accompanying drawings which form a part thereof.

The object of my invention is to provide a simple and effective coin controlled lock 15 adapted to various uses of vending machines and more particularly those requiring different prices for the article sold, my invention being adapted for operating the locking mechanism upon the deposition of one or 20 more coins of similar denomination according to the predetermined price to be paid for each delivery of merchandise or rental of an article, such as an opera-glass, from the case or vending machine.

25 My invention consists of a rotatable disk having space to receive a number of coins and which, upon rotation, will actuate the means for operating the locking bolt or catch of the case or vending machine.

30 My invention further consists in providing means in such rotatable disk whereby it may be adjusted to receive one or more coins before being in operative charged condition.

My invention also comprehends details of 35 construction which, together with the features above specified, will be better understood by reference to the accompanying drawings, in which:

Figure 1 is an elevation of my improved 40 coin controlled lock with the coin slot or rear plate removed; Fig. 2 is a cross section of my improved lock on line 2--2 of Fig. 1; Fig. 3 is a cross section of the same on line 45 3--3 of Fig. 1; Figs. 4 and 5 are, filling plates adapted to the coin disk of Fig. 1 for reducing its capacity to one or two coins; and Fig. 6 is an elevation of a modified form of coin disk.

A is the frame of the lock and is recessed 50 at A' to receive the coin disk and other cooperating parts and B is the coin slot plate having the coin slot C. When the plates A and B are placed one upon the other and secured together the coin slot will assume the

position indicated in dotted lines at C in 55 Fig. 1. These parts may be of stamped sheet metal, castings or otherwise as preferred.

D is the coin disk and is rotated by a knob F which extends through the plate A as 60 shown in Fig. 2. This disk D is provided with a plate D' so slotted that when combined with the disk D and secured by screws d it forms a slot or opening as shown at E. The dotted circles in Fig. 1 show the 65 four coins, in this particular case there being four and the uppermost coin or that last deposited is caused to project sufficiently beyond the disk that it is adapted to operate the levers L and M when the knob and disk 70 are rotated.

The disk DD' is provided with a notch G of considerable length in which a heel on the lever L engages, said lever being hinged to plate A and pressed toward the disk by the 75 spring l. This lever is also provided with a roller or pin P in the path of the coin and with a tooth S adapted to engage a similar tooth R on the lever M which is pivoted at M' to the plate A and adapted to operate the bolt or 80 lock of the case of the vending machine in any suitable manner. The lever M is provided with a roller N in the path of the coin and adapted to be operated thereby during the rotation of the disk for the purpose of 85 rocking the lever M. The lever M is normally held in the position shown by a spring m and is also returned to such position by said spring after being actuated by the coin.

The coöperation of the levers L and M is 90 such that the disk is moved to the right and when the coin lifts the roller P and the free end of its lever L, the tooth S is lifted from the tooth R of lever M, releasing said lever, and at the same time the lug of the lever L 95 is raised out of the notch G and permits the disk to continue its rotary movement. The coin next strikes the roller N and positively moves the lever M. A further movement of the coin disk will bring it to such position 100 that the coins will drop out of it by gravity and pass down the coin slot below the disk, and may be received in a suitable drawer, box or supported by a retainer device such as has heretofore been employed in coin controlled locks.

The pawl I is employed to prevent a backward movement to the disk DD' as it en-

gages a notch H in said disk as shown. When the disk is rotated to the right the pawl rides upon the outer periphery of the disk and is not effective to a return movement of the disk until the lever L has been raised, at which time it engages the ratchet teeth h upon the periphery of the disk. This then necessitates a continued rotation of the disk until the lever M is operated and the coins discharged. If now, the disk DD' be rotated further, it will continue until the original position is assumed and then, once again the lever L will drop into locking engagement with the notch G of the disk and at the same time this lever L will also lock the lever M which has been returned by its spring m. The positions of these parts will then be as in Fig. 1, namely, that in which the disk DD' when filled with coins will be in position where it may through the coin raise the lever L. When the parts are returned to the position shown in Fig. 1, they are retained there by the action of the spring actuated lever K the end of which is, by spring k, pressed against the shoulder J in the disk. This spring actuated lever K will permit the disk to have rotary movement to the extent of the notch G, namely, that necessary to receive the coin and to move it into position to raise the lever L, but will normally cause the disk to remain at the position shown, the same being that for receiving the coins. The distance between the notch H and the ratchet teeth h should be just greater than the throw of the disk preliminary to raising the lever L so as to prevent the pawl I engaging the teeth h before the lever M is unlocked. The lever K will swing around under a continued movement of the disk DD' permitting the parts G, H, h to pass freely over it, but it will reengage the shoulder J again when the normal position is reached once more.

If the disk DD' is made as shown in Fig. 4, it is evident that it will require four coins to operate the lock, but the shape of the part D' may be such as to make the lock operative with one or more coins. If a plate E' be fitted into the disk then it will be operative with two coins. If instead, the part E² be employed to fill up the coin chamber E of the disk, then one coin alone will be necessary to operate the lock. These adjustable parts may be used in connection with the disk or the plate D' thereof may be bodily changed with the parts E' or E² incorporated with the substituted part D'.

Instead of employing detachable parts for changing the number of coins required to make the lock operative, I may employ an adjustable arm e on the disk as shown in Fig. 4. As shown, this disk will require four coins to make it operative. If the arm e is adjusted to the lowermost dotted position then the disk will require three coins to

make it operative. If the arm e be adjusted to the uppermost dotted position, the disk will require two coins to make it operative. Any other suitable arrangement means may be employed in the disk for determining the number of coins required for making it operative. In all cases, the bottom or floor of the coin chamber E is raised or lowered to vary its depth, and it is evident that this may be accomplished in a variety of equivalent ways.

In practice I form the various parts of my improved coin controlled lock of stamped sheet metal, and while the same is most preferable, I do not restrict myself thereto.

While I prefer the construction shown as being a most excellent embodiment of my invention in practical commercial form, I do not limit myself to the details as they may be modified without departing from the spirit of the invention.

Having now described my invention, what I claim as new, and desire to secure by Letters Patent, is:—

1. In a coin controlled lock, the combination of a frame having a coin slot, a flat rotatable coin disk or carrier rotating in the plane of the coin slot, a coin actuated lock to lock the disk against rotation, and a coin actuated movable part for operating a lock or other device normally locked against movement by the coin actuated lock.

2. In a coin controlled lock, the combination of a frame having a coin slot, a rotatable coin disk or carrier having a recess adapted to receive two or more coins one of which extends beyond the periphery of the disk, a coin actuated lock to lock the disk against rotation, and a coin actuated movable part for operating a lock or other device normally locked against movement by the coin actuated lock.

3. In a coin controlled lock, the combination of a frame having a coin slot, a rotatable coin disk or carrier having means for permitting a limited rotary movement thereof, a spring actuated device to normally bring the disk or carrier into position to receive the coins from the coin slot, a coin actuated lock to lock the disk against rotation, a coin actuated movable part for operating a lock or other device normally locked against movement by the coin actuated lock, and means for preventing the backward rotation of the coin disk or carrier.

4. In a coin controlled lock, a rotatable coin disk having a recess extending part way through and opening to the periphery, and of a shape to receive a plurality of coins with one projecting beyond the periphery, combined with means to rotate the disk, a coin guide, a movable operating part to be operated by direct contact of the projecting coin, and a lock for the movable operating part in the path of the projecting coin and

arranged to be operated to release the movable operating part in advance of its being actuated by the coin.

5. In a coin-controlled lock, a rotatable coin-carrier comprising a pivotally mounted disk, and a coin-supporting member extending from one face of said disk, and having an angular slot or recess for supporting a plurality of coins in a single plane parallel with said disk.

10. 6. In a coin-controlled lock, a rotatable coin-carrier comprising a pivotally mounted disk, a coin-supporting member extending from one face of said disk, and having an angular slot or recess for supporting a plurality of coins in a single plane parallel with said disk, in combination with means for readily varying the coin-carrying capacity of said recess.

15. 7. In a coin-controlled lock, a rotatable coin-carrier comprising a pivotally mounted disk, and a coin-supporting member extending from one face of said disk, and having an angular slot or recess for supporting a plurality of coins in a single plane parallel with said disk, in combination with detachable means adapted to be inserted into said recess to close a portion thereof for varying the coin-carrying capacity of said

20. 8. In a coin-controlled lock, a coin-carrying disk having at one face thereof a recess opening to the periphery and extending inwardly across the axis of the disk, said recess being adapted to receive and support a plurality of coins in a single plane parallel with said disk, in combination with a movable part adapted to fit into said recess for varying the coin-carrying capacity 25 thereof, said part forming the support for the coins when inserted in said recess.

30. 9. In a coin-controlled lock, a rotatable coin-disk having an irregular-shaped recess for receiving a plurality of coins, so that one of the coins projects beyond the periphery of said disk, a device for normally locking said disk against free rotation, a movable member held locked by said device when the latter is in normal position, and means for rotating said disk to cause the projecting coin first to move said device into releasing position and then to operate said member.

35. 10. In a coin controlled lock, a rotatable disk for the coin having long notch G notch H shoulder J and ratchet teeth h in its periphery, combined with a frame having a coin slot for directing coins to and from the disk, a lever M for actuating a lock or other devices provided with a projection N in the 40 path of the coin carried by the disk, a locking lever L to lock the lever M and having a lateral projection P in the path of the coin carried by the disk, a locking pawl I to prevent backward movement of the disk beyond alinement with the coin slot, and

45. spring actuated lever K acting upon the shoulder J of the disk.

11. In a coin-operated lock, the combination of a locking device, a hand-operated disk having a recess in one face thereof, a 50 coin-guide forming a wall, which forms with said disk a chamber for the support and simultaneous movement of a plurality of coins for operating said locking device, and an operating member in the path of one of 55 the coins to be operated thereby, said locking device being arranged to unlock said member before the latter is actuated by the coin.

12. In a coin-controlled lock, the combination of a locking device arranged to be 60 moved by a coin, a movable member held by said locking device against operation, and having a recess for receiving a coin, an actuating member normally held locked by said device and adapted to be operated by a 65 coin in said recess after said coin has moved the locking device into releasing position, and hand-operated means for actuating said movable part.

13. In a coin controlled lock, the combination of a frame having a coin slot, a flat movable coin carrier movable in the plane of the coin slot, a coin actuated lock to lock the carrier against movement, and a coin actuated movable part for operating a lock 90 or other device having means whereby it is normally locked against movement by the coin actuated lock.

14. In a coin controlled lock, the combination of a frame having a coin slot, a movable 100 coin carrier, having a recess adapted to receive two or more coins one of which extends beyond the edge of the carrier, a coin actuated lock to lock the carrier against movement, and a coin actuated movable part for 105 operating a lock or other device normally locked against movement by the coin actuated lock.

15. In a coin controlled lock, the combination of a frame having a coin slot, a movable 110 coin carrier having means for permitting a limited movement thereof, a spring actuated device to normally bring the carrier into position to receive the coin from the coin slot, a coin actuated lock to lock the carrier 115 against movement, a coin actuated movable part for operating a lock or other device normally locked against movement by the coin actuated lock, and means for preventing the backward movement of the coin 120 carrier.

16. In a coin controlled lock, a flat movable coin carrier having a recess extending part way through and opening to the edge thereof and of a shape to receive a plurality 125 of coins with one projecting beyond the said edge, combined with means to move the carrier, a coin guide, a movable operating part to be operated by direct contact of the projecting coin, and a lock for the movable op- 130

- erating part in the path of the projecting coin and arranged to be operated to release the movable operating part in advance of its being actuated by the coin.
5. 17. In a coin controlled lock, a movable carrier for the coin having long notch a short notch a shoulder and ratchet teeth on its edge, combined with a frame having a coin slot for directing coins to and from the carrier, a lever for actuating a lock or other devices provided with a projection in the path of the coin carried by the carrier, a locking lever to lock the first mentioned lever and having a lateral projection in the path of the coin carried by the carrier, a locking pawl to prevent backward movement of the carrier beyond alinement with the coin slot, and spring actuated lever acting upon the shoulder of the carrier.
10. 18. In a coin controlled lock, a lock operating part adapted to be moved by a coin, combined with a coin carrier having a coin receiving recess formed therein of a plurality of connected portions arranged at an angle to each other and each of which is
15. capable of receiving and inclosing a single coin and one of said coins adapted to operate the lock operating part, and hand operated means for moving the coin carrier relatively to the lock operating part, whereby 30 a plurality of coins may be carried by a single carrier of small size and utilized for operating a common lock operating device.
19. In a coin-controlled lock, a locking device, an operating member normally held 35 locked against movement by said device, a movable coin - carrying member normally held locked by said device and adapted to hold the deposited coin in operative position, and means for actuating said coin-carrying 40 member to cause the deposited coin to actuate said device and said operating member in succession.

In testimony of which invention, I have hereunto set my hand.

JAMES W. PATTERSON.
